UNITED STATES PATENT OFFICE

JOHN F. LEVAN, OF ELKHART, INDIANA, ASSIGNEE TO THE O. M. EDWARDS COMPANY
INC., OF SYRACUSE, NEW YORK, A CORPORATION OF NEW YORK

AUTOMATIC ADJUSTABLE WEATHER-STRIP FOR WINDOW SASHES

Application filed April 4, 1930. Serial No. 441,625.

This invention relates to window constructions, particularly constructions for railway cars, busses and other vehicles, and has for its object, a particularly simple and efficient means for carrying a weather strip which contacts with one of the window stops and pressing the weather strip against said stop, which means also may if desired, be so mounted as to permit a widthwise adjustment within limits, so that the sash is readily fitted in window guides or post structures mounted in the window openings, which openings although intended to be exactly the same, vary somewhat in width.

15 The invention consists in the novel features and in the combinations and constructions hereinafter set forth and claimed.

In describing this invention, reference is had to the accompanying drawing in which 20 like characters designate corresponding parts in all the views.

Figure 1 is a fragmentary elevation of a window construction embodying my invention.

25 Figure 2 is a transverse sectional view on line 2—2, Figure 1.

Figure 3 is a transverse sectional view of the weather strip supporting member.

Figure 4 is an edge view of the sash showing the transverse slots therein.

30 Figure 5 is a fragmentary elevation of the weather strip supporting member showing the transverse slots therein.

1 designates the window frame or post 35 structure, which may be of any suitable form, size and construction, it being here shown as formed up of sheet metal, this frame 1 being fixed to the car body and confining the window opening in any suitable manner. The widthwise spacing of the post structures vary 40 within limits, as will be understood by those skilled in the art.

The frame or post structure is provided 45 with inner and outer window stops 2, 3 which form a sash guide or channel. These stops are secured to the post structure in any well known manner. One of the stops, preferably the outer stop, is formed with an internal offset channel portion 4 located beyond the 50 face of the sash 5. This stop 3 is also formed

with an outer rolled or beaded edge portion 6. The sash 5 is here shown as formed up of sheet metal, so that it is hollow and light. It is formed with a suitable reentrant groove 7 in which is received, a channel member 8 for receiving the margin of the glazing 9.

This invention relates to a weather strip and means for supporting it at the edge of the sash, and between the window stops 2, 3, in such a manner that it engages one of the stops and preferably, the stop formed with a recess 4, and extends into such recess, and means for pressing the weather strip against the wall of the recess.

10 designates the weather strip which is shown as mounted in a channel 11 provided on each edge of the sash between the stops 2, 3, the channel opening toward one of the stops, as the outer stop 3. This channel is provided in an adjustable member 12 having 15 —a body 1' shaped to snugly embrace the sash and be capable of a widthwise adjustment to conform, within limits, to the variations in spacing of the post structures. It will be understood that, there is a post structure at 20 each side of the sash, and also a weather strip and its supporting means at each edge of the sash, and that the weather strip and its supporting or holding means extends the full length of each edge of the sash. The 25 member 12 is preferably formed up of sheet metal to provide the channel which receives the sash, and the channel 11 for the weather strip 10, and said member 12 is also provided with a lip 13 on its outer side overhanging the edge of the stop 3 to deflect air currents away from the crevice or joint between the member 12 and the stop 3.

The adjustable member 12 and the channel 30 11 per se form no part of this invention, these 35 being the subject matter of the applications of Roy T. Axe, Ser. No. 431,579, filed February 26, 1930 and Ser. No. 375,133, filed July 1, 1929.

The weather strip is here shown, as 40 mounted in a holder 14 U shaped in cross section, slidably mounted in the channel 11, and the holder is interlocked with the channel and also with the sash, to permit transverse movement of the weather strip, but to prevent 45

endwise movement relatively to the sash during the raising and lowering of the sash. The connections between the weather strip and its holder 14, and the sash, are here shown 5 as pins 15 extending transversely through the holder 14 and the interposed weather strip, and projecting beyond the sides of the holder into transverse slots 16 formed in opposite side walls of the channel 11, and into trans- 10 verse slots 17 formed in the edge wall of the sash.

The weather strip and its holder is pressed outwardly by springs 18 interposed between the bottom of the channel 11 and the bottom 15 of the holder 14. The springs illustrated, are coiled compression springs. Any suitable spring or resilient means may be used. The outer margin of the weather strip, as before stated, projects into the recess 4 and engages 20 the walls thereof, and is pressed in weather tight engagement therewith by the springs 18.

The sash is provided with the usual sash holders, not shown, or so-called sash locks, which hold the sash closed, and also hold it 25 at different elevations in the sash guide, and these sash locks or holders are usually arranged so that they press the sash toward the outer stop when the sash is closed. The sash holder or lock construction forms no part of 30 this invention.

This invention is particularly advantageous in that the weather strip 10 is always pressed toward the outer stop into snug engagement therewith, so that the sash is 35 weather tight regardless of whether the lip 13 is, or is not employed. Also, the weather strip being carried by an edgewise adjustable member 12, can be accurately located relatively to the recess 4 to effectively perform its 40 function.

What I claim is:

1. The combination of a sheet metal window sash and guide therefor, the guide being provided with inner and outer stops opposed 45 to the front and rear walls of the sash, the stiles of the sash having straight flat side walls, a weather strip carried by the edge wall of the sash stile within the guide, and spring means acting on the weather strip to thrust 50 the same transversely of the edge of the sash against one of the stops.

2. The combination of a window guide in the form of a channel, a sash movable in the guide, the guide being formed with inner 55 and outer stops opposed to the front and rear faces of the sash, and the sash having means for carrying a weather strip in the guide at the edge of the sash, the guide being formed with an internal offset recess in one of 60 the stops thereof located beyond the plane of the adjacent side face of the sash, the recess being arranged to overlap said side face, and a weather strip carried by said means within 65 the guide and having an edge portion located in said recess, and spring means tending to

thrust the weather strip laterally relatively to the edge of the sash against the walls of the recess.

3. The combination with a window sash and guide therefor, the guide being provided 70 with inner and outer window stops opposed to the front and rear walls of the sash, the guide being formed with an internal offset recess portion extending beyond the plane of one side face of the sash, and a weather strip 75 carried by the sash and located at the edge of the same, and having an edge portion extending into the offset recess of the window guide, and spring means acting on the weather strip to thrust the same laterally relatively to the 80 edge of the sash and press the same against the wall of said offset recess.

4. The combination of a window sash and guide therefor, the guide being provided with inner and outer window stops opposed to the 85 front and rear walls of the sash, the sash being provided with a transversely extending channel on the edge wall thereof between the stops, the channel opening toward one of the 90 stops, a weather strip mounted in the channel and movable therein transversely of the edge wall of the sash, and spring means interposed between the bottom of the channel and the weather strip to thrust the weather strip against one of the stops, said channel having 95 an outer wall disposed at the edge of the sash between the weather strip and the surface of the guide between the inner and outer stops so that the channel is open only at its side toward one of the stops. 100

5. The combination of a window sash and guide therefor, provided with inner and outer window stops opposed to the front and rear walls of the sash, the sash being provided with means forming a channel at the edge 105 thereof between the stops, the channel opening toward one of the stops, a weather strip holder mounted in the channel to slide transversely of the edge of the sash, a weather strip carried by said holder and projecting 110 out of the channel and engaging one of the stops, and spring means interposed between the bottom of the channel and said holder, and tending to thrust the weather strip against one of the window stops. 115

6. The combination of a window sash and guide therefor, provided with inner and outer window stops opposed to the front and rear walls of the sash, the sash being provided with means forming a channel at the edge 120 thereof between the stops, the channel opening toward one of the stops, a weather strip holder mounted in the channel to slide transversely of the edge of the sash, a weather strip carried by said holder and projecting out of 125 the channel and engaging one of the stops, and spring means interposed between the bottom of the channel and said holder, and tending to thrust the weather strip against one of the window stops, said weather strip 130

holder and the means providing the channel in which it slides being provided with a pin and slot connection, the slot of which extends transversely of the edge of the sash.

5 7. The combination of a window sash and guide therefor, provided with inner and outer window stops opposed to the front and rear walls of the sash, the sash being provided with means forming a channel at the 10 edge thereof between the stops, the channel opening toward one of the stops, a weather strip holder mounted in the channel to slide transversely of the edge of the sash, a weather strip carried by said holder and projecting 15 out of the channel and engaging one of the stops, and spring means interposed between the bottom of the channel and said holder, and tending to thrust the weather strip against one of the window stops, said weather 20 strip holder and the means providing the channel in which it slides and the edge of the sash, being provided with a pin and slot connection, the slots of which extend transversely of the edge of the sash.

25 8. The combination of a sash and window guide therefor, the guide being provided with inner and outer window stops opposed to the front and rear walls of the sash, a member mounted on the edge of the sash and comprising a body embracing the margin of the 30 sash and coacting with the front and rear faces thereof, said member being provided with a channel located at the edge of the sash and opening toward one of the stops, a weather 35 strip located in the channel and engaging one of the stops, and a spring located in the channel and acting to thrust the weather strip outwardly against one of the stops.

40 9. The combination of a sash and window guide therefor, the guide being provided with inner and outer window stops opposed to the front and rear walls of the sash, a member mounted on the edge of the sash and comprising a body embracing the margin of the 45 sash and coacting with the front and rear faces thereof, said member being provided with a channel located at the edge of the sash and opening toward one of the stops, a weather 50 strip located in the channel and engaging one of the stops, and a spring located in the channel and acting to thrust the weather strip outwardly against one of the stops, said member being adjustable edgewise relatively to the sash.

55 10. The combination of a sash and window guide therefor, the guide being provided with inner and outer window stops opposed to the front and rear walls of the sash, a member mounted on the edge of the sash and comprising a body embracing the margin of the sash and coacting with the front and rear faces thereof, said member being provided with a channel located at the edge of the sash and opening toward one of the stops, a weather

strip located in the channel and engaging one of the stops, a spring located in the channel and acting to thrust the weather strip outwardly against one of the stops, said member being formed up of sheet metal with the 70 side walls tensioned to grip the sash and hold the said member in its adjusted position.

11. The combination with a window guide, a sash movable in the guide, the guide having front and rear stops opposed to the front and rear faces of the sash, the guide being formed with an internal offset recess in one of the stops thereof, located beyond the plane of the adjacent side wall of the sash, the recess being arranged to overlap said side 75 face of the sash, a member comprising a body portion in the form of a channel frictionally embracing the margin of the sash member and formed with means within the guide for supporting a weather strip extending transversely of the edge of the sash and engaging the wall of said recess, the weather strip being mounted to move transversely of the edge of the sash, and a spring carried by said 80 member and acting on the weather strip tending to thrust the same transversely of the edge of the sash, and against the wall of said recess.

12. The combination of a window guide, a sash movable in the guide, the guide being formed with inner and outer stops opposed 95 to the front and rear faces of the sash, a member mounted on the edge of the sash comprising a body portion formed with a channel, the side walls of which frictionally embrace the sash, said member being adjustable edge-wise relatively to the sash, said member being formed with a channel extending transversely of the edge of the sash and opening toward one of the window stops, a weather 100 strip mounted in said channel and coacting with one of the walls of the guide, the sash and the walls of said channel being formed with transversely extending slots, and the weather strip being provided with pins extending into the slots, and springs located 110 within the channel and acting on the weather strip tending to move the weather strip against one of the stops.

In testimony whereof, I have hereunto signed my name, at Elkhart, in the county of 115 Elkhart, and State of Indiana, this 1st day of April, 1930.

JOHN F. LEVAN.
